SAFE CABINET LOCKING DEVICE

Raymond L. Stegmaier, Arlington, Va.

Application April 20, 1956, Serial No. 579,698

5 Claims. (Cl. 312—217)

(Granted under Title 35, U.S. Code (1952), sec. 266)

The invention described herein may be manufactured and used by or for the Government of the United States of America for governmental purposes without the payment of any royalties thereon.

The present invention relates to the locking of drawers for sliding units of safes, filing cabinets or the like.

An object of the invention is to provide a positive locking mechanism for safes, filing cabinets or the like where all units are controlled by a common movable portion under the control of a primary locking means which movable portion requires a distinct and separate movement for the locking and unlocking of said units.

Other objects of the invention will appear more fully from the description taken in connection with the accompanying drawings wherein,

Fig. 1 is a perspective view partly broken away showing the inside of a filing cabinet fitted with the improved locking mechanism thereof.

Fig. 2 is a detailed view of the locking mechanism associated with the top drawer of Fig. 1 showing the normal or locked position of the respective parts.

Fig. 3 is a detailed view of the locking mechanism associated with the middle drawer of Fig. 1, showing the normal position of the mechanism with the catch stud of the respective drawer abutting the same.

Fig. 4 is a detailed view of the locking mechanism associated with the lower drawer of Fig. 1 showing the normal position of the mechanism with the respective drawer extended for use.

The embodiment of the invention is particularly adapted to provide special utility in connection with drawers or sliding units of a filing cabinet. It contemplates a simple and thoroughly practicable means which is primarily intended to be associated with a plurality of drawers or sliding units arranged in a tier or stack, and which provides secure and reliable means for locking all drawers or sliding units in the closed positions and preventing the opening of any or all of the same except by the use of a proper movable portion. Furthermore, the locking mechanism is of such character as to admit of the greatest possible freedom in the use of the individual drawer or sliding units, that is, certain drawers or sliding units may be in use while the remaining ones are held securely locked.

Referring to Fig. 1, there is shown a filing cabinet comprising a casing 11 with a plurality of sliding units 12. The top drawer is equipped with a combination dial means 14.

In accordance with the invention, the improved locking mechanism assembly 13 for each of the drawers 12 includes a latch dog 17 (Figs. 2, 3, and 4) each of which is mounted pivotally to a respective supporting bracket 18 provided with flanged margins. The supporting bracket 18 is within and fixed upon the frame part of casing 11. The latch dog 17 is provided at one arm with an inclined slot 17a and at the other with a beveled offset 17b having a shouldered latching indent 17c which in the normal

2

position of parts rests on the flanged side margin 21 of supporting bracket 18. A control rod 16 extends upright and is common to all of the sliding units 12. The control rod 16 is provided with a plurality of actuating pins 19, one for each contained sliding unit 12. The actuating pin 19 is adapted to engage and remain seated in the inclined slot 17a of latch dog 17.

The inclined slot 17a in the tail of the latch dog 17 is the median in the translation of the vertical reciprocal movement of the control rod 16 into the arc of travel of the head 17b of latch dog 17. This concept is more readily understood when said slot is taken as the approximate hypotenuse of a right triangle. The length of the hypotenuse (slot) is determined by the vertical distance 15 through which the control rod 16 is to move in the operation of the locking mechanism 13. The length of the vertical adjacent side of said right triangle defines the arc of travel of the head of the latch dog 17 from the locked to the unlocked position. The angle between the 20 hypotenuse and the vertical adjacent side is determined to translate the vertical movement of the control rod 16 into the arc of travel of head 17b of the latch dog 17.

When the head 17b of the latch dog 17 has been raised from its normal position by dropping the control rod 16, 25 the catch stud 15 (Figs. 2 and 3) projecting from the side of each sliding unit 12 passes beneath said raised latch dog 17 as the unit is moved inwardly to the closed position. Upon moving the control rod 16 to the top position, the head 17b of the latch dog 17 is returned to 30 the normal or locked position and the catch stud 15 of the respective sliding unit 12 is retained (Fig. 2). It is seen by reference to the drawing (Fig. 3), that when an open sliding unit 12 is moved inwardly after the head 17b of the latch dog is in the normal position, the projecting 35 stud 15 will abut against the latch dog, thereby preventing the closure of the sliding unit.

The feature of the locking mechanism assembly 13 which permits freedom in the use of the individually opened sliding unit 12, while holding the remaining sliding units 12 securely locked, has special application in 40 the safe keeping of confidential documents and similar matter. Unauthorized personnel having unnoticed access to a filing cabinet while in use could only see information stored in the opened sliding unit and would be unable to 45 avail themselves of the information stored in the remaining closed units. Further, the use of said filing cabinet by authorized personnel would insure that proper security measures to be taken by the same in that an attempted closure of an open unit 12 when the latch dog 17 is in the 50 normal position, would be prevented.

The movement of the common control rod 16 is adapted to be operated by a movable portion, here the upper sliding unit 12, which in turn is under the control of a primary locking means, here shown to be a combination dial 55 securing means 14 (Fig. 1). This primary locking means 14 is therefore common to the other sliding units 12 in the cabinet and controls the locking and unlocking thereof. The primary locking means 14 can be supported in the front of any sliding unit 12 or at a fixed position at a 60 convenient point within the casing 11, e.g., the upper right hand corner of the casing.

In the normal position with all the sliding units 12 of the cabinet closed, the control rod 16 is held in an up position by the upper sliding unit 12. This position of 65 the control rod 16 operates to lock and hold the latch dog 17 in the normal position, i.e., the beveled offset having the shouldered latching indent rests on the flanged side margin of the supporting bracket 18 and is held in that position. This position of the latch dog 17 serves to restrain the withdrawal of the respective sliding unit 12 from the closed position as projecting catch stud 15 (Fig. 2) will abut against and not pass under the latch

dog head. When it is desired to unlock the sliding units, the moveable portion, upper sliding unit 12, is pulled forward thus releasing the control rod 16 for positive automatic movement by conventional means to the lowest position of vertical travel. This in turn raises the heads of the latch dog 17 due to the coaction of the actuating pin 19 and the contour of the inclined slot. The sliding units are then unlocked. Should any or all the sliding units 12 be left in the open position after the top unit 12 is closed which movement would return the latch dogs 17 to the normal position of the locking mechanism 13, the remaining sliding units 12 could neither assume the closed position nor could they be locked (Fig. 3). To close and lock the remaining sliding units 12, it would be necessary to withdraw the movable unit 12, thus raising the heads of the latch dogs 17, complete the closure of the sliding units 12 and finally return the top unit 12 to back to the closed position.

It should be understood, of course, that the foregoing disclosure relates to only a preferred embodiment of the invention and that it is intended to cover all changes and modification of the example of the invention herein chosen for the purpose of the disclosure, which do not constitute departures from the spirit and scope of the invention set forth in the appended claims.

What is claimed and desired to be protected by letters Patent of the United States is:

1. In a locking mechanism for slidable members comprising; a supporting bracket with a flanged side and bottom margin and a recess in the upper margin; a latch dog pivotally mounted on said bracket having a plurality of arms with the axis of one arm in coincidence with the horizontal direction, when said latch dog is in the normal or locked position and the axis of the other arm in an obtuse relationship thereto, intersecting at the point of the pivotal mounting, said obtuse arm having an elongated slot centered therein, and situated to always be in registry with the recess in the upper margin of the supporting bracket, said horizontal arm having a bevelled offset at an angle thereto extending below the lower margin and from the end thereof, part way to the pivotal mounting with a shouldered latching indent situated on the lower edge thereof half the length of the bevelled offset from the end of said horizontal arm which is adapted to rest on the flanged side margin of the bracket; a control rod vertically disposed mounted for reciprocal movement along the longitudinal axis of said control rod; an actuating pin of cylindrical shape fixed perpendicularly on said control rod and of sufficient length to be seated and retained in the elongated slot of the latch dog; a means for actuating the vertically disposed control rod reciprocally along the longitudinal axis, whereby, in combination with the actuating pin and the elongated slot of the latch dog, the locking mechanism is raised from the normal or locked position to the unlocked position; and, a catch stud fixed on one side of the slidable member and projecting therefrom adapted to be engaged by the locking mechanism on the inward travel of said slidable member and to be retained by the normal position of the latch dog when the catch stud is at the end of inward travel.

2. In a locking mechanism for slidable members comprising; a supporting bracket with flanged side and bottom margins; a latch dog pivotally mounted on said bracket having a plurality of arms with the axis of one arm in coincidence with the horizontal direction, when said latch dog is in the normal or locked position, and the axis of the other arm in an obtuse relationship thereto, said obtuse arm having an inclined slot centered therein and said horizontal arm having a bevelled offset at an angle thereto, extending below the lower margin and from the end thereof part way to the pivotal mounting, with a latching indent therein, adapted to rest on the flanged side margin of the bracket; a control rod vertically disposed mounted for reciprocal movement

along the longitudinal axis of the rod; an actuating pin fixed perpendicularly on said control rod and retained in the elongated slot of the latch dog; means for actuating the control rod reciprocally, whereby, in combination with the actuating pin and inclined slot of the latch dog, the mechanism is raised from the locked position to the unlocked position; and, a catch stud projecting from the side of a slidable member adapted to engage the locking mechanism on the inward travel of that member and to be retained by the latch dog when in the normal position at the extreme inward position.

3. In a locking mechanism for slidable members comprising; a supporting bracket with a side margin at an angle thereto; a latch dog pivotally mounted on said bracket having a plurality of arms with the axis of one arm in coincidence with the horizontal direction, when said latch dog is in the normal or locked position, and the axis of the other arm in an obtuse relationship thereto, said obtuse arm having an elongated slot centered therein and said horizontal arm having an offset at an angle thereto, extending below the lower margin thereof, with a shouldered latching indent therein, adapted to rest on the side margin of said supporting bracket; a control rod vertically disposed mounted for longitudinal reciprocal movement; an actuating pin fixed on said control rod end extending perpendicular therefrom, seated in the elongated slot of the latch dog; means for moving the control rod reciprocally, whereby, to raise the latch dog from the normal or locked position; and, a catch stud fixed on the side of the slidable member adapted to engage the locking mechanism on the inward travel of said slidable member and to be retained by the locking mechanism when in the normal or locked position.

4. In a locking mechanism for a plurality of tiered sliding members of filing cabinets or the like comprising in combination; a casing containing a plurality of tiered members; a fixed upright extending the length of the contained members within and a part of said casing; a plurality of locking mechanisms mounted on said fixed upright consisting of a supporting bracket with a flanged side and bottom margin and a recess in the upper margin, a latch dog pivotally mounted on said bracket having a plurality of arms with the axis of one arm in coincidence with the horizontal direction, when said latch dog is in the normal or locked position, and the axis of the other arm in an obtuse relationship thereto intersecting at the point of the pivotal mounting, said obtuse arm having an elongated slot centered therein, and situated to always be in registry with the recess in the upper margin of the supporting bracket, said horizontal arm having a bevelled offset at an angle thereto, extending below the margin and from the end thereof, part way to the pivotal mounting with a shouldered latching indent situated on the lower edge thereof, half the length of the bevelled offset from the end of said horizontal arm which is to rest on the flanged side margin of the bracket; a control rod vertically disposed and common to all members mounted for reciprocal movement along the longitudinal axis of the rod; a plurality of actuating pins of cylindrical shape, individual to each locking mechanism fixed perpendicularly on the common control rod and of sufficient length to be seated and retained in the elongated slot of the latch dog; means controlled by a combination dial securing means for actuating the control rod reciprocally, whereby, in combination with the plurality of actuating pins and the plurality of elongated slots of the respective latch dogs, the plurality of locking mechanisms are raised from the normal or locked position to the unlocked position; and, a plurality of catch studs individual to one side of a tiered sliding member adapted to be engaged by the respective locking mechanism on the inward travel of the respective sliding member and to be retained by the respective normally positioned latch dog when said catch stud is at the end of inward travel.

5. In a locking mechanism for a plurality of sliding

members of filing cabinets or the like comprising in combination; a casing containing the plurality of slideable members; a fixed support common to the members; a plurality of locking mechanisms attached to the fixed upright consisting of a supporting bracket with a side margin at an angle thereto, a latch dog pivotally mounted on said bracket having a plurality of arms with the axis of one arm in coincidence with the horizontal direction, when said latch dog is in the normal or locked position, and the axis of the other arm in an obtuse relationship thereto, said obtuse arm having an elongated slot centered therein, and said horizontal arm having an offset at an angle thereto, extending below the lower margin thereof, with a shouldered latching indent therein, adapted to rest on the side margin of the bracket; a control rod 15 vertically disposed and common to all members mounted

5 for longitudinal reciprocal movement; a plurality of actuating pins fixed on the control rod individual to each locking mechanism and seated in the inclined slot of the latch dog; means controlled by a primary locking means for moving the control rod reciprocally, thereby, raising the plurality of latch dogs from the normal position; and, a plurality of catch studs one each for a slideable member adapted to engage the respective locking mechanism on the inward travel and to be retained by the mechanism 10 when in the normal position.
